UNITED STATES PATENT OFFICE.

WALTER J. FENSTERER, OF ENGLEWOOD, NEW JERSEY.

DESIGN FOR A LIGHT-TRANSMITTING GLASS ARTICLE.

50,506.

Specification for Design. Patented Mar. 27, 1917.

Application filed February 7, 1917. Serial No. 147,263. Term of patent 7 years.

To all whom it may concern:

Be it known that I, WALTER J. FENSTERER, a citizen of the United States, residing at Englewood, in the county of Bergen and State of New Jersey, have invented a new, original, and ornamental Design for Light-Transmitting Glass Articles, of which the following is a specification, reference being had to the accompanying drawing, forming part thereof.

The drawing represents a side view of a gas shade showing my new design.

The design consists, substantially, of the representation of a series of garlands hung

from a series of urns which are interposed between the garlands. Along that rim of the glass article which faces the concaved sides of the garlands, there extends a border formed of a series of oblong rectangular figures and interposed circular figures.

The design is applied to gas shades, electric light shades, light bowls, light domes, light urns and similar articles.

I claim:

The ornamental design for a light transmitting glass article substantially as shown and described.

WALTER J. FENSTERER.
